UNITED STATES PATENT OFFICE.

WILLIAM H. JAMES, OF BOSTON, MASSACHUSETTS, ASSIGNOR TO THE
E. HOWARD WATCH AND CLOCK COMPANY, OF SAME PLACE.

DEVICE FOR PREVENTING ACCIDENTAL CLOSING OF ELECTRIC CIRCUITS IN SIGNAL-BOXES.

SPECIFICATION forming part of Letters Patent No. 484,206, dated October 11, 1892.

Application filed February 16, 1892. Serial No. 421,681. (No model.)

To all whom it may concern:

Be it known that I, WILLIAM H. JAMES, of Boston, in the county of Suffolk and State of Massachusetts, have invented certain new and 5 useful Improvements in Devices for Preventing the Accidental Closing of an Electric Circuit in Signal-Boxes, of which the following is a specification.

It is the object of my invention to provide 10 means for preventing the closing of an electric circuit in a signal box or apparatus in the event of the breakage of the actuating-spring.

My invention consists in connecting one end 15 of the actuating-spring with a pivoted arm or other suitable device, which arm when the spring is intact is supported by the latter in contact with means which permits of the circuit being closed through the mechanism or movement of the box; but when the spring 20 breaks, the arm will drop so as to permanently break the circuit through the movement.

Reference is to be had to the annexed drawings, and to the letters and figures marked thereon, forming a part of this specification, 25 the same letters and figures designating the same parts or features, as the case may be, wherever they occur.

Of the drawings, Figure 1 represents a front view of the mechanism or movement of the 30 signal box or apparatus having my improvements applied thereto. Fig. 2 is a side view of the same.

The movement or mechanism shown in the drawings is such as is adapted to have the 35 circuit closed and opened in any predetermined series or combination of series that may be desired, though it is not essential to my invention that said means should be of the form or character of that herein shown.

40 It will appear from the description herein-after given that my invention is applicable to any movement or signaling device in which electricity is employed and which embraces a spring as the actuating power.

45 In the drawings, *a* is the front plate, and *b* is the back plate, of the movement.

c is the winding-arbor, on which a ratchet *d*, having only one tooth, (not shown,) as is common in movements of this kind, is securely 50 fastened.

e designates a wheel, which is provided with

a long hub bored to fit loosely upon the arbor *c*. On the hub of wheel *e* is fastened the contact-wheel *f* with its hub. To wheel *e* is attached a click and its spring, said click engaging with the ratchet *d*, as is usual in devices of this kind. 55

g designates the actuating-spring, one end of which is attached to the arbor *c*, around which the spring is for the most part coiled, 60 and the other end being attached to a stud *h*, which is rigidly fastened to a movable part, a swinging arm *i*, pivoted so as to turn freely on a stud *j*.

k designates a metallic stud fastened rigidly 65 to a plate *l*, which plate is in turn fastened to a piece of insulating-fiber or other similar material *m*.

n designates a rubber tube enveloping the stud *k*, and *o* is a metallic pin fastened to the 70 stud *k* and passing through the rubber tube *n*, so that when the arm *i* is raised and supported by the spring *g*, as shown in Fig. 1, said arm may rest against or bear upon the pin *o*.

p designates a metallic spring mounted on 75 the insulating-fiber *q* and so located in relation to the teeth of the contact-wheel *f* that the said teeth as the wheel is revolved may come into contact with the said spring *p*. One end 2 of the circuit-wire is attached to the 80 spring *p*, and the other end 3 of the said circuit-wire is attached to the plate *l*. When a tooth of the contact-wheel *f* is in contact with the spring *p*, the electric circuit will be completed through the plate *l*, stud *k*, pin *o*, arm 85 *i*, and the various metallic parts of the movement to the teeth of the contact-wheel and the spring *p*.

As the movement of a signal-box is usually 90 incased in a close-fitting case, in the event of the spring *g* breaking it is very liable as it uncoils to come into contact with the contact-spring *p*, the spring *g* commonly breaking near the end where it was attached to the stud *h*. Furthermore, one of the teeth of the contact- 95

wheel *f* is liable to jump into contact with the spring *p* when the spring *g* breaks, thereby closing the circuit permanently until repairs can be made. By my improvements these difficulties and objections are overcome, since 100 the instant a spring breaks the arm *i* drops, so as to break the electrical connection of the

same with the plate or contact-piece *l*, with which, as has before been explained, one pole of the electric circuit is connected.

It will be observed that the form of the plate or contact-piece *l* and its connections, as also that of the pivoted arm *o*, may be varied without departing from the nature or spirit of my invention, it being essential only that the said plate or contact-piece should be insulated from other parts of the signaling movement, and that the pivoted arm should be electrically connected with such other parts and be adapted to be raised and supported by the actuating-spring in electrical contact with the contact plate or piece *l* and to fall away therefrom and break electrical connection through the movement upon the breakage of the actuating-spring.

Having thus described the nature of my invention and explained a way of constructing and using the same, though without attempting to set forth all of the forms in which it may be made or all of the modes of its employment, I declare that what I claim is—

1. A signal-movement comprising in its construction a plate or contact-piece, with which

the wire of one pole of an electric circuit is connected, insulated from other parts of the movement, a movable part in electrical connection with the movement and adapted to be supported in contact with and fall away from the contact plate or piece, and the actuating-spring adapted to be connected with the said arm and support the same in contact with the plate or contact-piece. 30

2. A signal-movement comprising in its construction a stud *k*, provided with a pin *o*, connected with one pole of an electric circuit and insulated from the other pole, a movable part *i*, connected with the other pole of an electric circuit, and an actuated spring adapted to be connected with said arm and support the same in contact with the pin *o*, as set forth. 35

In testimony whereof I have signed my name to this specification, in the presence of 45 two subscribing witnesses, this 15th day of February, A. D. 1892.

WILLIAM H. JAMES.
